UNITED STATES PATENT OFFICE.

HARVEY C. LOWRIE, OF DENVER, COLORADO.

COMBINATION-LOCK.

No. 850,942.

Specification of Letters Patent.

Patented April 23, 1907.

Application filed March 29, 1904. Serial No. 200,608.

To all whom it may concern:

Be it known that J. HARVEY C. LOWRIE, a citizen of the United States, and a resident of the city and county of Denver, in the State of Colorado, temporarily residing at New York, in the county of New York and State of New York, have invented new and useful Improvements in Combination-Locks, of which the following is a specification.

10 My invention relates to a combination-lock having a plurality of bolts in the form of disks which are free to revolve in either direction and adapted to be rotated into and out of engagement with a suitable keeper, 15 said bolts requiring separate adjustment for opening the lock.

Locks of this character as heretofore constructed have had the bolts or disks mounted upon a central support in contact with each other or in contact with the central operating-spindle which is revolved for turning the disks, and when a disk has been thereby adjusted to its proper position it is liable to be moved out of position by the succeeding 25 movements of the spindle which are required for adjusting the remaining disk or disks, this being because of frictional contact of the disks with each other or with the spindle.

The main object of my invention is to 30 move all liability of a disk being moved from its adjusted position by any part of the mechanism which must be moved for adjusting the remaining disks, and this I accomplish by mounting the disk or disks that are not directly coupled to the rotating mechanism independently of said mechanism, so that necessary movements of said mechanism will not be communicated to a disk that has been once properly adjusted.

40 My said invention consists in the features of construction to be hereinafter described, and particularly pointed out in the claims hereunto annexed.

Referring to the drawings furnished and 45 forming a part of this specification, Figures 1 and 2 are front and rear views, respectively, of a lock embodying my invention. Fig. 3 is a central vertical section of the same on line 33 of Fig. 1. Fig. 4 is a rear view of the lock 50 with the rear portion of the casing removed and a portion of the main casing broken away. Fig. 5 is a plan view of the face of the lock, a portion of the casing being broken away.

The lock illustrated in the drawings is designed as a door or drawer lock and may be provided with any desired number of locking disks or bolts. Three disks or bolts A, A', and A² are shown, and they are rotatively mounted in the lock-casing B, so that they will project beyond the face b of said casing for engagement with a suitable keeper C, the latter being secured to the casing D of the drawer or door D' on which the lock is mounted. Each of said disks or bolts is in the form of a centrally-perforated circular disk having a segment cut therefrom on a line a, which coincides with the face of the lock-casing when the disk or disks are properly adjusted to open the lock, said disks being then wholly within said casing and free from engagement with the keeper C, as will be readily understood.

The lock-casing B comprises a front wall b', a substantially annular wall b², and a rear plate or wall b³. The disks or bolts A, A', and A² are supported at their peripheries by the annular wall b² of the casing, said wall being provided with grooves b⁵, in which said bolts or disks are rotatively mounted. The front wall b' of the casing is provided with a central hub b⁴, in which the operating-spindle E is mounted, said spindle having a dial F secured thereto on the outside of the casing and being provided with a suitable knob or handle e, by means of which the spindle is rotated for adjusting the disks or bolts.

The disk or bolt A is centrally perforated, as at a', and around said perforations is a series of notches a², provided for receiving a pin or pins e', projecting from the spindle E, the engagement of the pin with the notches serving to rotatively couple the disk A to the operating-spindle.

The rear end of the spindle E projects through the central perforations a' in the disks or bolts A' and A² and is screw-threaded to receive a clamping-nut e², which clamps the disk A between the inner end of the nut and a shoulder e³ on the spindle E, said disk being thus locked to the spindle, while the spindle is at the same time locked to the front wall of the lock-casing. The nut e² projects through the rear wall of the casing and is provided with a milled head e⁴, by means of which the nut may be withdrawn from the spindle for changing the combination of the lock, as will be hereinafter explained.

The bolt-keeper C is provided with a slot c for each of the disks or bolts of the lock, and any one of the disks or bolts that may be in engagement with the keeper will be sufficient to hold the lock even though the other bolts be out of engagement therewith.

The face of the lock is provided with extensions or flanges d, which project laterally beyond the sides or beyond the annular wall of the casing, said extensions being provided with screw-holes d', by means of which the lock is secured to the edge of the door or drawer, the latter being cut out to receive the annular wall of the lock, as clearly shown.

For confining the lower portion of the lock in place a spur g is provided at the under side of the casing, which may be driven into the wood or fitted into a hole provided therefor, as clearly shown in Fig. 3.

The lock-keeper C is secured to the casing of the door or drawer in proper position to register with the lock, and the front wall b' of the lock-casing is made to extend upwardly beyond the face of the lock, as at b", to prevent a knife-blade or other device from being inserted between the face of the lock and the keeper for the purpose of moving the bolts.

The opening in the face of the lock through which the bolts or disks are inserted is slightly greater than smallest diameter of the disks, so that the latter can only be inserted in the casing by presenting the smallest diameter of the disks to the opening, as indicated in dotted lines in Fig. 4.

The rear plate b² of the casing is secured to the annular wall b¹ by means of screws p, and at its upper edge said plate is provided with a slotted flange b³, which completely covers the face of the lock at all points not required to be open for the proper movements of the rotating bolts.

As already explained, the disk or bolt A is rotatively coupled to the spindle E, so that when the latter is revolved the disk A is also revolved. Said disk or bolt A is provided with a projection or pin i, which is in line with a pin i' on the disk A', and the latter is provided with another pin i² in line with a pin i³ on the disk A². By turning the spindle E so that the pin i on the disk A engages with the pin i' on the disk A' the latter may be revolved for causing its pin i² to move the disk A² by contact with the pin i³. The disk A² may be thus adjusted to its proper position for opening the lock, and by reversing the direction of rotation of the spindle the disk A' may be properly adjusted without liability of disturbing the adjustment of the disk A². When these two disks have been adjusted, the direction of rotation of the spindle is again reversed for adjusting the disk A. When all three disks have been adjusted in line with each other and with their straight edges a in line with the face of the lock, said

disks will be free from the keeper C, and the drawer or door may be opened. When the door or drawer is closed, two or three turns of the spindle E will throw the disks or bolts out of line with each other and in engagement with the keeper, as will be readily understood.

The movements of the spindle for opening the lock are supposed to be known only to the persons authorized to open the same, and said movements are guided by the numbers on the dial F in a well-known manner. When it is desired to change the combination, the nut e² is partially withdrawn or unscrewed from the spindle E, and the latter is pulled slightly out of the lock-casing and turned so that the relative positions of the disk A and spindle E may be changed by shifting the pin or pins e' from one notch a² to another, as will be understood, the spindle being pushed back in the desired position and the nut e² again tightened. The required movements of the spindle for opening the lock will then be governed by numbers on the dial F, differing from the numbers of the original combination.

For preventing the nut e² from becoming detached from the spindle E there is a screw k tapped into the rear end of the spindle, said screw having a head k', which engages with a shoulder on the interior of the nut e². This screw k is withdrawn from the spindle sufficiently to permit the nut e² to be withdrawn the required distance for changing the unlocking combination when desired, the latter operation being readily performed without opening the lock-casing or disturbing any of its parts.

It is to be noted that the bolts or disks A' and A² are wholly supported by the lock-casing and that they are not in any manner connected with the operating-spindle except through the medium of the projecting pins which are provided for transmitting motion from one disk to another, and when said pins are not in engagement with each other the disks A' and A² cannot be moved. This is an important and valuable feature of my invention, as it removes all liability of an adjusted disk being disturbed by subsequent movements of the operating-spindle which may be necessary for adjusting other disks.

While I have illustrated and described a lock designed for use on a door or drawer, it is to be understood that the particular form of the lock, as well as the details of construction, may be widely varied without departure from my invention.

Having thus described my invention, what I claim as new, and desire to secure by Letters Patent, is—

In a lock of the character described, the combination of a plurality of circular disks having a segment removed therefrom, a suit-

able casing provided with grooves in which said disks are peripherally supported, said disks being adapted by rotation to be projected from or retracted within said casing,
5 pins or projections on said disks for imparting motion from one disk to another, and means for rotating one of said disks.

In testimony whereof I have hereunto set my hand in presence of two subscribing witnesses.

HARVEY C. LOWRIE.
